ABSTRACT: An ignition device for internal-combustion engines, wherein a spark gap is, energized by a voltage pulse, has a transformer having primary and secondary windings, the secondary winding being connectable to the spark gap. An amplifier is connected to the primary winding and a magnetic circuit provides a magnetic field having an intensity which changes between determined values thereof. A galvanomagnetic sensing element is disposed in the magnetic field and is responsive to the changes in the field intensity. The sensing element is connected to the amplifier for controlling the flow of current through the primary winding so as to develop voltage pulses across the secondary winding for energizing the spark gap.

IGNITOR FOR INTERNAL COMBUSTION ENGINES

Our invention relates to an ignitor for internal combustion engines wherein a spark gap is energized by a voltage from the secondary of a transformer in which the primary winding is excited in response to mechanically controlled short-interval changes.

A mastering of the ignition process is important for the efficient operation of vehicles powered by internal-combustion engines. Present day ignition systems almost all utilize mechanical means which most often comprise break contacts actuated by a cam shaft. Such means are unfortunately subjected to considerable wear.

The first attempts at reducing the vulnerability of ignitors are exemplified by the popularly termed transistor or thyristor ignitions which, in addition to increasing the ignition output relative to the above devices, reduce the current load of the break contacts, and thereby reduce the wear caused by burn-off. However, reducing the intermittent current causes, at the same time, an increase in the unreliability of contact which can easily lead to undesired disturbances especially when the thyristor fires. In addition, the mechanical wear associated with camshaft control is not at all reduced.

It is also known to use a photoelectric technique wherein a cylinder provided with slits rotates between a light source and a photo cell and initiates the firing process via an appropriate transistor circuit at a reference value obtained from the photo element. Although this arrangement reduces wear and renders the breaker mechanism superfluous, it too has proved very vulnerable to disturbances particularly when used in a vehicle.

Accordingly, it is an object of our invention to provide a new and improved ignitor which overcomes the aforementioned disadvantages of the known techniques.

It is still another object of our invention to provide an ignitor in which no wear occurs between parts thereof moving relative to each other. Subsidiary to this object it is an object of our invention to provide an ignitor wherein the energization of the spark gap is controlled in dependence upon changes in the flux intensity of a magnetic field.

According to a feature of the invention, a galvanomagnetic resistor, which acts to electrically control the primary side of the transformer, for example via an amplifier, in response to the movement of a permanent magnet relative to the galvanomagnetic resistor. A rotating magnet assembly is preferably used in achieving the objects of the invention. The galvanomagnetic resistance consists, preferably, of a so-called field plate as disclosed, for example, in U.S. Pat. Nos. 3,267,404 and 3,260,980. Such field plates may be substituted by other types of galvanomagnetic resistance devices such as, for example, galvanomagnetic PN diodes.

The field plate can be placed upon a carrier, for example, in the shape of a narrow strip. It is preferable to use a stationary field plate since this makes contacting simpler and the two current leads easily accessible. The leads to the field plate are preferably laid over the carrier. Typically, the cylindrical magnet carrier is seated on the distributor shaft of the motor and is equipped along its periphery with a number of equally spaced control magnets, this number corresponding, for example, to the number of cylinders of the motor. The changes which occur in the field plate with respect to its resistance value R are plotted as a function of the magnitude of the angle of rotation of the distributor shaft in the diagram according to FIG. 1.

The invention will now be elucidated with reference to the drawings in which:

FIG. 1, as already mentioned, is a graph depicting the variation of the resistance of the field plate as a function of the angular movement of the distributor shaft.

FIG. 2 is a schematic representation, partially in section, of a preferred embodiment of the invention in which a permanent magnet is coaxially mounted to a distributor shaft.

FIG. 3 is a plan view of the embodiment illustrated in FIG. 2.

FIG. 4 is a schematic diagram of an amplifier and transformer used to translate the control signal initiated by the field plate to a voltage for energizing the spark gap.

FIG. 5 is a schematic diagram of the amplifier preferred for use with the embodiment of the invention according to FIG. 2.

Referring to FIGS. 2 and 3, a ring-shaped permanent magnet 1 is provided at its top and bottom surfaces with coaxially positioned annular plates 2, 3 consisting of magnetic permeable material such as soft iron. The magnet 1 and plates 2, 3 are mounted on shaft 4 so as to be coaxial therewith, the shaft 4 being, for example, the distributor shaft of an internal-combustion engine. The annular plates 2, 3 function as poles for the magnet. The plates 2, 3 are bridged at periodic intervals by a soft iron yoke 6 which is laterally arranged and contains a field plate 5. This is achieved by providing one of the two rings 2, 3 for example, the upper ring 3, with equidistant radial projections 3' while the other ring 2 maintains a narrow distance from the bottom leg of the yoke 6, this distance being unchanged during the entire rotation. The profile of the bulges 3' is adjusted to the profile of the upper leg of the yoke 6 and ends accordingly in a pointed tip as does the latter so that the magnetic flux across the yoke is closed only for short intervals of time during the travel of each projection 3' past the upper leg of the yoke 6.

The soft iron yoke 6 is subdivided into two parts, preferably through its center. The disc-shaped field plate 5 comprised of semiconductor material is disposed between these two parts in such a manner that the entire magnetic flux which closes across the yoke also crosses the field plate 5. The electrical terminals of the field plate are indicated by reference numeral 7 and the stationary base plate which carries the yoke is indicated by reference numeral 8.

Although the foregoing discloses an embodiment wherein the permanent magnet and its pole plates are mounted coaxially with the distributor shaft, it is also possible to mount a permanent magnet on the shaft so that it is eccentric with respect to the shaft axis.

The diagram corresponds qualitatively to the characteristic which may be expected in connection with the embodiment of FIGS. 2 and 3. The primary advantage of the above-described device is that it is simple to produce and affords high operational reliability, particularly with regard to imperviousness to contamination.

The changes which occur in the galvanomagnetic resistance member according to FIG. 1 during the operation of such a device or similar devices can be made to act upon the primary side of an ignition transformer in a number of ways. Especially preferred is the switching arrangement illustrated in FIG. 4, which can be further developed to the arrangement shown in FIG. 5.

Referring first to FIG. 4, the spark gap 11 is energized by the secondary winding of the ignition transformer or ignition coil. The base of a switching transistor 13 lies at the center tap of a voltage divider formed with fixed resistance 14 and the galvanomagnetic resistance 15 which can correspond, for example, to the field plate 5 of a device according to FIGS. 2 and 3. The fixed resistor 14 is in the emitter-base circuit and the field plate 15 is in the collector-base circuit. The primary coil of the ignition transformer 12 is connected in series with the fixed resistor 14 and with the emitter of the switching transistor 13. The elements 14 and 15 of the voltage divider are dimensioned so that the switching transistor 13 conducts when the field plate 15 is not passed by magnetic flux. The supply voltage which can be, for example 6 volts direct voltage, is supplied as shown in FIGS. 4 and 5.

When the magnetic flux acts upon the field plate 15, its resistance value rises. Transistor 13 turns off interrupting the current through the primary winding of the ignition transformer 12 and releases an ignition voltage at the spark gap 11 in accordance to Lenz's law. In the interest of optimum effectiveness, it is recommended that the following conditions be established:

1. The keying ratio or duty cycle should be chosen so that even at high impulse frequency, which corresponds to a high r.p.m. of the shaft, the occurrence of the highest possible field strength in the field plate is assured, and
2. The leading edge of the control pulses must be sufficiently steep.

The requirement of condition (1) can be fulfilled with control magnets having an appropriately small width. Condition (2) is fulfilled by using shaping circuits which are controlled by the transistor. In this connection, reference is made to the embodiment illustrated in FIG. 5 which can be regarded as an optimum embodiment of the invention when taken together with a device according to FIGS. 2 and 3.

In FIG. 5, the voltage divider 14, 15, which is connected together with the transistor 13 is already discussed in connection with FIG. 4, delivers a suitable control voltage to a shaping circuit for increasing the steepness of pulse edges with transistors 13 and 16. Resistance 14 is again a fixed resistance, resistance 15 is galvanomagnetic sensing element or member. The shaping circuit with the transistors 13 and 16 has the characteristic of flipping from one stable state to another when the voltage at the base of the transistor 13 rises to a specific threshold value. This is caused by the amplification which is determined by resistances 17, 18 and 19 in coaction with the feedback via the common emitter resistance 20. The steeper voltage characteristic at the collector of the transistor 13 controls, via resistor 18, a transistor 21 whose saturation current is so high that it can switch a power transistor 22 which is connected in series with the primary winding of the ignition transformer. Ignition firing occurs when the circuit triggers at the leading edge of the voltages at the base of transistor 13 and transistor 22 suddenly interrupts the current through the primary winding of the ignition transformer 12. The high, positive voltage which occurs at this moment at the emitter of the transistor 22 is limited by the Zener diode 23 to a specific value in order to protect the transistor 22. The bistable flip-flop circuit provided in a device according to FIG. 5 thus ensures the appearance of a voltage at the spark gap 11 which is virtually independent on the instantaneous movement speed, more particularly on the rotary speed of the controlling permanent magnet.

In this connection, attention is called to the fact that the galvanomagnetic resistance of a device of the present invention can also control other bistable flip-flop circuits, particularly with such circuits built-up of semiconductor components. Bistable flip-flops deliver a voltage pulse at the triggering instant with required intensity in the secondary portion of the ignition transformer and so also at the spark gap.

The advantages of a device according to the invention include affording the use of magnetically controlled field plate resistance several of which can be used in a single device. The invention provides a contact-free ignition-voltage switch that meets the requirements for the rugged operation of gasoline engines. The life span afforded by the invention can be considered to be unlimited since mechanical wear and tear are virtually completely eliminated. Most of all, the disadvantages associated with the known devices in respect to the occurrence of resonance, frequency unreliability and in respect to making contact are eliminated, the latter introducing a very critical time delay when the closing angle is unfavorable.

To those skilled in the art it will be obvious upon a study of this disclosure that our invention permits of various modifications and may be given embodiments other than particularly illustrated herein, without departing from the essential features of the invention and within the scope of the claims annexed hereto.

We claim:

1. An ignition device for an internal combustion engine hav-

- ing spark gap means and a shaft rotatable in synchronism with the rotation of the engine, comprising a transformer having a primary winding and having a secondary winding for connection to the spark gap means, a permanent magnet attached to said shaft so as to be rotatable therewith, a stationary magnetizable yoke structure disposed adjacent to said rotatable magnet structure and having a field gap, said rotatable magnet and said yoke structure conjointly defining a magnetic circuit for providing a magnetic field having an intensity that changes between values thereof in synchronism with the rotation of said shaft and said engine, a galvanomagnetic resistor disposed in said gap and having a resistance changeable in response to changes in said magnetic field, and an amplifier comprising a voltage divider, a switching transistor and a power transistor connected in cascade, said voltage divider consisting of two two-pole members, one pole of one member being joined to one pole of the other member so as to form a tap, one of said members being said galvanomagnetic resistor and the other of said members being a fixed resistance, said tap being connected to the base of said switching transistor, the other of said poles of said one member being connected to the collector of said switching transistor and the other of said poles of said other member being connected to the emitter of said switching transistor to convert the collector current of said switching transistor changes to pulses in response to said changes in said galvanomagnetic resistor, said switching transistor and said power transistor conjointly defining a shaping network for increasing the steepness of the edges of said pulses, said power transistor being connected to said primary winding of said transformer, whereby said power transistor interrupts the current in said primary winding in response to said pulses.
2. An ignition device according to claim 1, comprising a driver stage connected intermediate said power transistor and said shaping network.
  3. An ignition device according to claim 1, comprising a Zener diode connected across the output of said power transistor for protecting the latter.
  4. An ignition device according to claim 1, said shaping network including a additional transistor connected to the output of said switching transistor so as to define a bistable flip-flop circuit conjointly with the latter, whereby said flip-flop circuit switches to one state with the occurrence of the leading edges of said pulses and switches to the other state with the occurrence of the trailing edges of said pulses.
  5. An ignition device according to claim 1, comprising two single-pole plates mounted on said shaft so as to be concentric therewith, said permanent magnet being annular and disposed so as to be sandwiched intermediate said plates and coaxial with said shaft, said yoke structure being disposed laterally of said permanent magnet and said pole plates, said yoke being in two parts arranged so as to accommodate said galvanomagnetic resistor therebetween, said yoke and said pole plates with said permanent magnet forming a magnetic circuit the magnetic flux of which passes through said galvanomagnetic resistor; at least one of said pole plates having a noncircular shape so as to cause said magnetic circuit to sequentially close and open as said plates and said permanent magnet are rotated on said shaft whereby the flow of flux crossing said galvanomagnetic resistor is sequentially interrupted.
  6. An ignition device according to claim 5, said one plate having projections at respective locations equally spaced about the periphery thereof, whereby said projections sequentially pass close to said yoke to sequentially close and open said magnetic circuit when said shaft rotates.
  7. An ignition device according to claim 5, said two parts of said yoke each consisting of soft iron.
